UNITED STATES PATENT OFFICE.

HERMAN A. POPPENHUSEN, OF HAMMOND, INDIANA, ASSIGNOR TO GREEN ENGINEERING COMPANY, OF EAST CHICAGO, INDIANA, A CORPORATION OF ILLINOIS.

FIRE ARCH.

Application filed August 4, 1921. Serial No. 489,713.

To all whom it may concern:

Be it known that I, HERMAN A. POPPENHUSEN, a citizen of the United States, residing at Hammond, in the county of Lake 5 and State of Indiana, have invented new and useful Improvements in Fire Arches, of which the following is a specification.

This invention relates to fire-arches for furnaces and more particularly to fire-arches which are made of a plurality of tiles or bricks arranged in rows extending from the front to the inner end of the arch and suspended from a framework or super-structure above the same.

One object of my invention is to provide an adjustable means for supporting the tiles at the inner ends of the rows so that said tiles may be brought into proper contact with the next adjacent tiles to the rear regardless of any variation that may exist in the thickness of said tiles, and thus avoid providing gaps between the tiles at the inner ends of the rows through which cold air may be drawn downward from 25 above the arch into the combustion chamber therebelow.

A further object of my invention is to support the adjustable tiles in a manner that none of the weight of the wall structure 30 thereabove is on the same, and thus enable said tiles to be readily removed without tearing down or otherwise disturbing said wall structure.

The invention consists further in the matters hereinafter described and more particularly set forth in the appended claims.

In the accompanying drawings—

Fig. 1 is a perspective view of one-half of a fire-arch structure embodying the 40 features of my invention;

Fig. 2 is an enlarged vertical sectional view taken through the inner end of a row of tiles and the wall structure above the same and showing the adjustable tile and 45 the structure for suspending the same;

Fig. 3 is a front elevational view of one of the adjustable tiles and showing the supporting structure therefor;

Fig. 4 is a sectional view taken on line 50 4—4 of Fig. 2, and

Fig. 5 is a top plan view of one of the structures shown in Fig. 3.

The fire-arch structure shown in the drawings comprises a plurality of tiles or

blocks 1, 1 arranged in rows extending 55 at an inclination upward and inward from the front wall of the furnace setting, as customary in arches of this general character. As shown in Figs. 1 and 2, the tiles 1, 1 in each row rest or bear flatwise against each other throughout their front and rear vertical faces. Also the tiles 1 of one row contact along their side edges with the tiles in the adjacent rows. In the arch structure shown in Fig. 1, there is a tile 60 or brick 1^a at the end of each row adjacent the front wall of the furnace, and this tile 1^a extends downward below the under or heat radiating surface of the remainder of 65 the tiles in the row, to provide a step in 70 the arch at said front wall to prevent cold air drawn into the combustion chamber through the inlet opening for the fuel from following and chilling said arch surface, as disclosed in the copending application 75 of Thomas A. Marsh, Serial No. 258,845 and filed October 19, 1918.

Above the arch are I-beams 2, laterally spaced apart and extending from the front to the inner or rear end of the arch structure. These beams 2 are located between the rows of tiles 1 and have their base flanges 2^a in channels or grooves in the sides of the adjacent tiles for suspending the 80 same from said beams. Extending transversely across the arch above the beams 2, 2 are cross-girders or channel members 3, 3, also spaced apart and supported at their ends in the side walls of the furnace setting. Engaged with the lower flanges of these 90 girders are hook-shaped members 4, 4, which embrace the headed upper edges of the beams 2 and support the beams from said cross-members 3, as shown in Fig. 1.

While the tiles 1 have substantially the 95 same dimensions, yet said tiles vary in thickness sufficiently to cause the tiles 1 at the inner ends of the several rows to be out of alignment, transversely, as shown in Fig. 4. To complete each row, there is a 100 tile or block 5 at the inner end thereof, and it is essential that this tile 5 rest or contact flatwise throughout its inner vertical face with the adjacent face of the tile 1 next behind the same, in order to prevent a gap 105 or space being formed between such tiles and thus prevent cold air being drawn through the arch from above into and

chilling the combustion chamber therebelow. To accomplish this object, I provide the following construction.

As illustrated in Fig. 4, the inner ends of the I-beams 2 all terminate in the same vertical plane. Extending across the spaces between the I-beams 2 at the inner ends thereof are flat plates 6. These are supported by said beams 2 in a manner permitting the plates 6 to be slid or adjusted endwise of said beams for the purpose to be presently described. The form of connection shown consists of a flat flange 7 along the margin of the plate at one side and an upwardly offset flat flange 8 on the opposite side of the plate. The flange 7 rests or bears on the upper edge of one I-beam 2, and the offset flange 8 rests on the like edge of the opposite I-beam 2 by overlapping the flange 7 of the plate 6 supported in part by said beam, as shown in Fig. 3. Each plate 6 at its side edge provided with the offset flange 8 is also provided with a lower flange 9 engaging under the headed upper edge of the associated I-beam 2.

There is a plate 6 for each of the end tiles 5, and each is suspended from its plate 6 by a member 10 arranged in front of its plate 6. The member 10 is provided at its upper end with a pair of depending lugs 11, 11, spaced laterally apart and adapted to engage behind upwardly projecting flanges 12 on the outer edge of the plate. These flanges 12, 12 terminate short of each other and provide slots or spaces 13, 13 allowing the member 10 to be engaged with its plate 6 by passing the lugs 11 inward between the flanges 12 and then sliding the member 10 to one side in a direction to position the lugs 11 back of said flanges 12. To remove the member 10 from its plate 6, the member is moved laterally in the opposite direction to register the lugs 11 with said slots 13 and withdrawing the member 10 outward from said plate.

The member 10 is provided at its lower end with a hook-shaped flange 14 projecting outward and disposed to enter a groove 15 in the rear face of the tile or block 5, as shown in Fig. 2. This suspends the tile 5 from its member 10.

The members 10 being slidably mounted on the I-beams 2, said members, in building or erecting the arch in a furnace, may be adjusted endwise of said beams to position and support the end tiles 5 in proper contact with the tiles 1 immediately to the rear thereof, regardless of any variations that may exist in the tiles 1 in each row, as shown in Fig. 4. Thus proper joints may be had between the tiles 5 and the tiles 1 next behind the same, and prevent spaces being formed to allow cold air to be drawn into the combustion chamber through the arch at such points.

To complete the arch structure, a wall 16 is built above the tiles 5 at the inner end of the arch. This wall 16 is erected after the

tiles 1 and 5 have been placed in position and suspended from the I-beams 2. The wall 16 is built on the plates 6 after they have been adjusted for the purpose mentioned, and they serve to support said wall. None 70 of the weight of the wall 16 is on said end tiles 5. After said wall 16 is erected, the space between the bottom of said wall and the tops of the tiles 5 is filled with brick 17, which is the only part of said wall 16 which 75 need be cut away when a tile 5 is to be released for repair or otherwise. After removing the section 17, the tile 5 may be removed by lifting it off the hooked end of its member 10 and withdrawing the tile outward from the member 10. Each plate has an upwardly projecting end flange 18 engaging said wall 16 at the rear thereof as an aid in supporting the same. Said plate 6 is also provided with a depending flange 85 19 adjacent its rear or inner end. This flange extends between and engages the I-beams 2 between which the plate is located to position the plate and guide it in its adjustment.

The tiles 1^a are suspended from the I- 90 beams 2 by adapter plates 1^b in the same manner as described in said copending application filed by Thomas A. Marsh.

While I have shown and described herein in detail a fire-arch structure embodying the 95 features of my invention, it is to be of course understood that the details of construction and arrangement of parts illustrated may be variously changed and modified without departing from the spirit and scope of my invention. 100

I claim as my invention:

1. In a fire-arch, two laterally spaced beams, a row of tiles between said beams and suspended therefrom, said tiles being in contact with each other, a plate extending between said beams above said tiles, an end tile at one end of said row and in front of said plate, and means for suspending said end tile from said plate, said plate having engagement with said beams so that said end tile may be adjusted into contact with the tile to the rear thereof. 110

2. In a fire-arch, two laterally spaced beams, a row of tiles between said beams and suspended therefrom, a plate extending between said beams above said tiles, an end tile at one end of said row and in front of said plate, and a member interposed between said plate and said end tile and engaging the latter for suspending said end tile from said plate, said plate having sliding engagement with said beams so that said end tile may be adjusted into contact with the tile to the rear thereof. 115

3. In a fire-arch, two laterally spaced beams, a row of tiles between said beams and suspended therefrom, a plate extending between said beams above said tiles, an end tile at one end of said row and in front of 130

said plate, and a member interposed between said plate and said end tile and depending from said plate, said member having lugs at its upper end releasably engaged behind upper flanges on said plate and a hook shaped lower end engaging in a groove in said end tile, said plate being slidably mounted on said beams so that said end tile may be adjusted into contact with the tile to the rear thereof.

4. A fire-arch, comprising an upper structure including laterally spaced beams extending from the front to the rear end of said arch, a plurality of rows of tiles, one in each of the spaces between said beams and suspended therefrom, the tiles in each row being in contact with each other, plates at the inner ends of said rows above the same and extending between and slidably supported by the beams at the sides of said rows, said plates having side flanges, one resting on the adjacent beam and the other overlapping the side flange of the plate on the opposite beam, end tiles at the inner ends of said rows in front of said plates and contacting with the tiles at the rear thereof, and members interposed between said plates and said end tiles and connected with both for suspending said end tiles from said plates.

5. In a fire-arch, the combination with laterally spaced beams extending from front to rear of the arch, of a row of tiles in each

of the spaces between the beams and suspended therefrom, substantially flat plates, one at the inner end of each row of tiles and extending across and supported by the adjacent beams for individual adjustment thereon, end tiles at the inner ends of said beams, one for each plate, and hooks to the rear of said end tiles, and suspending the same from said plates by having releasable connection with the front edges of said plates and the rear of said end tiles at their upper and lower ends, respectively.

6. In a fire-arch, the combination with laterally spaced beams extending from front to rear of the arch, of a row of tiles in the spaces between said beams and suspended therefrom, substantially flat plates, one at the inner end of each row of tiles and extending across and supported by the adjacent beams for individual adjustment thereon, end tiles at the inner ends of said beams, one for each of said plates, an upwardly extending wall at the inner end of the arch with the portions of said wall between the beams resting on and supported by said plates, and hooks suspending the end tiles from said plates.

In testimony that I claim the foregoing as my invention, I affix my signature this 1st day of August, A. D. 1921.

HERMAN A. POPPENHUSEN.
